(57) **CLAIM**

The ornamental design for clip of card holder, as shown and described.

DESCRIPTION

FIG. 1 is a perspective view of a clip of card holder showing my new design according to a first embodiment;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view of a clip of card holder showing my new design according to a second embodiment;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a perspective view of a clip of card holder showing my new design according to a third embodiment;

FIG. 16 is a front view thereof;

FIG. 17 is a rear view thereof;

FIG. 18 is a left side view thereof;

FIG. 19 is a right side view thereof;

FIG. 20 is a top plan view thereof;

FIG. 21 is a bottom plan view thereof;

FIG. 22 is a perspective view of a clip of card holder showing my new design according to a fourth embodiment;

FIG. 23 is a front view thereof;

FIG. 24 is a rear view thereof;

FIG. 25 is a left side view thereof;

FIG. 26 is a right side view thereof;

FIG. 27 is a top plan view thereof;

FIG. 28 is a bottom plan view thereof;

FIG. 29 is a perspective view thereof in a use state;

FIG. 30 is a perspective view thereof in another use state.

(Continued)

FIG. 31 is a perspective view of a clip of card holder showing my new design according to a fifth embodiment; FIG. 32 is a front view thereof; FIG. 33 is a rear view thereof; FIG. 34 is a left side view thereof; FIG. 35 is a right side view thereof; FIG. 36 is a top plan view thereof; and, FIG. 37 is a bottom plan view thereof. The broken lines depict portions of the clip of card holder and form no part of the claimed design.
